METHOD FOR CONVERTING HYDRO-CARBONS

John Stewart Harrison, Cleveland Heights, Ohio,
assignor to The Standard Oil Company, Cleveland, Ohio, a corporation of Ohio

Application December 2, 1930, Serial No. 499,507

8 Claims. (Cl. 196—60)

In the production of motor fuel by cracking petroleum, it has been customary to heat the raw material, generally a gas oil fraction, under liquid-phase conditions, and finally distill from the products a desired motor fuel fraction. Some effort also has been made to crack in vapor-phase, by heating vaporized hydrocarbons at a comparatively high temperature range. Each of these offer some advantages, but accompanied by limitations in general. I have now found, however, that limitations as encountered in these respective systems may be obviated, and with unexpected advantages and results generally. The invention, then, comprises the features hereininafter fully described and particularly pointed out in the claims, the following description and the annexed drawing setting forth in detail certain illustrative embodiments of the invention, these being indicative, however, of but a few of the various ways in which the principle of the invention may be employed.

In said annexed drawing:—

The sole figure is a semi-diagrammatic elevation of apparatus contemplated in the invention.

Referring more particularly to the drawing, there is shown a heating means, which involves an initial heater 2, most advantageously for instance in the form of a so-called coil or bank of connected tubes, and exposed to products of combustion of a suitable furnace 3, or at least such as to be out of the hottest portion, so as to receive an initial heating not too abruptly. From this, a further or main heater 4 advantageously of so-called coil type, connects with the heater 2 and is located in the hotter or radiant portion of the furnace chamber. From the heater 4, a connection 5 leads to a liquid-phase digester tank or drum 6, guarded against heat-loss, as by an insulating jacket or a flue-gas jacket, and preferably in vertical position. From this in turn a connection 7 proceeds to a lower-pressure drum 8, a pressure regulating valve 9 being interposed in the line. Connected with the drum 8 is a distillation or fractionating tower 10, the detail of which may vary, but which may contain baffles or plates, preferably such as to provide a bubbling of vapors through a liquid layer. In the connection 11 enroute from the drum 8, partial condensers 12, 13, 14 are desirably introduced, these being of any convenient construction facilitating the passage of the hot vapors from the drum through passways such as to be in heat exchange relation with the feed line 15. The latter connects to the heating coil 2, and proceeds from a

pump 16 and drum 17 having further connections, among which is an input line 18 connecting through partial condensers 19, 20, 21 and thence to a feed pump 22 supplied from any suitable source of raw-material. A further distillation or fractionating tower 23 desirably is arranged, having an input line 24 proceeding from the partial condensers 19, 20, in which heat exchange is had with the feed line 18. From the tower 10 a drain line 25 leads to drum 17, and a similar drain line 26 is provided for tower 23. A connection 27 in continuation extends to a heater 28, which again preferably is of so-called coil type, and placed in a position to receive heat, but not the more direct heat of the furnace. Preferably, such heater may be positioned in the same setting 3 already referred to, and in the portion thereof leading to the stack off-take 29. From the heater 28, a connection leads to a further main heater 30, which may be included in the same furnace setting 3 before referred to. Such heater then in turn connects with a heater section 31 which again may be positioned in its own controlled furnace, or preferably may be likewise provided in the same setting aforesaid, such heater being in the high temperature or radiant portion thereof, and again for instance being of so-called coil type. From this, a connection 32 leads to drum 8.

In the practice of the process, the desired raw material, for example a gas oil fraction, is forwarded from a suitable source of supply through pump-line 22 and heat exchangers 21, 20, 19 and connection 18 to drum 17. From this, material is forwarded by pump 16 to heat exchangers 13, 12, (valve b being opened, and valves b' and b'' being closed for this purpose) and through line 15 to the coil 2, where the oil is preheated, and is then forwarded to the main heating coil 4, and thence through line 5 to drum 6. The conditions in the heating coil portion of the system and the digester drum 6 are such as to maintain liquid-phase cracking, the pressure on the drum as determined by valve 9 being on the order of 400—1200 pounds per square inch, for instance, and the temperature in the neighborhood of, but not exceeding 975° F. Preferably, a pressure of about 1,000 pounds per square inch and a temperature of about 925° F. as maximum from the heating coil, is provided. Lower pressure prevails in the drum 8, such pressure being less than 200 pounds per square inch, and preferably on the order of about 100 pounds. At the same time, material is being supplied to coil 30. The material for this portion

of the system may be forwarded from a suitable source of supply by pump 33 through heat exchanger 14, (valves b' b'' being closed for such alignment), and valve 34 being open and valve 35 being closed. The material then proceeds through preheating coil 28, main heater sections 30, 31, and thence through connection 32 to drum 8 to mingle in heated state with the material entering at the same time from the liquid-phase portion of the system. Conditions in the portion 30, 31 of the system are maintained for vapor-phase cracking, the temperature being above 1,000° F., and the pressure not exceeding 200 pounds per square inch. Preferably, a temperature of 1025-1125° F. is maintained for the maximum as leaving coil 31. As material supplied by pump line 33, any desired petroleum distillate may be employed. Advantageously, a heavy naphtha may be used, for instance a heavy crude naphtha. From the drum 8, vapors proceed through line 11 to the heat exchangers 12, 13, 14 acting as partial condensers, the operation being controlled by the amount of cooler oil shunted therethrough by the control valves v. Condensate from the partial condensers is taken off by connections 36, 37, and may be returned to desired points of the system, or may be otherwise disposed of as preferred. A drain line 38 from the drum 8 provides for removal of accumulating unvaporized material. From the exchanger 14, the vapors proceed to tower 10, where distillation and fractionation occurs, the uncondensed vapors proceeding from the top of the tower to partial condensers 19, 20, and the unvaporized ends are discharged by the connection 25 to drum 17 to mingle with the incoming feed, and recycle as desired. From the partial condenser 20, the remaining vapors proceed through connection 24 to tower 23, where distillation and fractionation proceeds, the remaining vapors passing by connection 39 from the top of the tower to partial condenser 21, and thence to final condenser 40 and receiver 41. The unvaporized accumulation in the bottom of tower 23 is taken off through connection 26, and with valve 42 open and valves 35 and 44 closed, proceeds through cooler 45 to receiver 46. Receivers 41 and 46 may be provided with draw-off connections 47, 48 and gas connections 49, 50. By opening valve 44, and closing valves 42 and 35 the products from tower 23 may be directed into drum 17 for recycling if desired.

With advantage, the material fed through the vapor-phase cracking portion of the system may be a heavy cracked distillate as obtained in the fractionating portion of the system itself. For this, valves 42, 44 may be closed, and valve 35 may be opened, and valve 34 further being closed, pump 51 may then forward the heavy cracked distillate from the fractionating portion of the system itself into the vapor-phase coil system 28, 30, 31. Heat exchanger 14 will at this time be cut back into the line 15, the valves b', b'' being opened and valve b being closed. The procedure otherwise is as described.

Other modes of applying the principle of the invention may be employed, change being made as regards the details described, provided the features stated in any of the following claims, or the equivalent of such, be employed.

I therefore particularly point out and distinctly claim as my invention:

1. A process of altering the boiling point of hydrocarbons, which comprises heating a petroleum distillate under pressure, then digesting in a zone 75 guarded against substantial heat-loss and being

without temperature-rise from external heat and providing liquid-phase cracking conditions, releasing the material into a zone of lower pressure, heating another petroleum distillate at a higher temperature but lower pressure providing substantially vapor-phase cracking conditions, and independently discharging into admixture in the same lower pressure zone aforesaid. 5

2. A process of altering the boiling point of hydrocarbons, which comprises heating a petroleum fraction at not exceeding 975° F., then digesting in a zone guarded against substantial heat-loss and being without temperature-rise from external heat and providing liquid-phase cracking conditions under a pressure of 400-1200 10 pounds per square inch, releasing the material into a zone of lower pressure not exceeding 200 pounds, heating another petroleum distillate at a temperature of 1025-1125° F. at pressure not exceeding 200 pounds per square inch providing 20 substantially vapor-phase cracking conditions, and independently discharging into admixture in the same lower pressure zone aforesaid. 15

3. A process of altering the boiling point of hydrocarbons, which comprises heating a petroleum fraction at not exceeding 925° F., then digesting in a zone guarded against substantial heat-loss and being without temperature-rise from external heat and providing liquid-phase cracking conditions under a pressure of about 25 30 1000 pounds per square inch, releasing the material into a zone of lower pressure, heating another petroleum distillate at a temperature of 1025-1125° F. at pressure not exceeding 200 pounds per square inch providing substantially vapor-phase 35 cracking conditions, and independently discharging into admixture in the same lower pressure zone aforesaid. 5

4. A process of altering the boiling point of hydrocarbons, which comprises heating a petroleum distillate, then digesting in a zone guarded against substantial heat-loss and being without temperature-rise from external heat and under 40 pressure producing liquid-phase cracking conditions, releasing the material into a zone of lower 45 pressure, separately heating another petroleum distillate at a higher temperature and lower pressure under substantially vapor-phase cracking conditions, and discharging such vapor-phase output into the aforesaid lower-pressure zone. 50

5. A process of altering the boiling point of hydrocarbons, which comprises heating a petroleum distillate, then digesting in a zone guarded against substantial heat-loss and being without 55 temperature rise from external heat and under pressure providing liquid-phase cracking conditions, releasing the material into a zone of lower pressure, separately heating a lighter distillate at a higher temperature and lower pressure under substantially vapor-phase cracking conditions, 60 and discharging such vapor-phase output into admixture in the aforesaid lower-pressure zone. 65

6. A process of altering the boiling point of hydrocarbons, which comprises heating a petroleum distillate, then digesting in a zone guarded against substantial heat-loss and being without 70 temperature-rise from external heat and under pressure producing liquid-phase cracking conditions, releasing the material into a zone of lower pressure, separately heating another petroleum distillate at a higher temperature and lower pressure under substantially vapor-phase cracking conditions, discharging such vapor-phase output into admixture in the aforesaid lower-pressure zone, distilling from the products a motor fuel, 75

and returning heavy ends therefrom as the aforementioned second petroleum distillate.

7. A process of altering the boiling point of hydrocarbons, which comprises passing a stream of a petroleum distillate through a heating zone under high pressure into the lower part of a digester zone providing a time period of reaction under liquid-phase cracking conditions, simultaneously passing another stream of a petroleum distillate 10 through a vapor phase heating zone under a higher temperature and lower pressure than that first mentioned, and discharging the stream from said latter heating zone and the stream from the upper portion of said digesting zone together into 15 a lower pressure zone.

8. A process of altering the boiling point of hydrocarbons, which comprises passing a stream

of a petroleum distillate through a heating zone under high pressure providing liquid-phase cracking conditions and thence into the lower portion of a digesting zone, whereby to reduce the velocity of the stream and provide a time 5 period of reaction simultaneously passing another stream of a petroleum distillate through a vapor phase heating zone under a higher temperature and lower pressure than the aforementioned, discharging products from said latter heating zone 10 and from the upper portion of said digesting zone into a lower pressure zone, fractionating vapors from said lower pressure zone, and supplying a heavy distillate therefrom as the aforementioned second stream of distillate. 15
